UNITED STATES PATENT OFFICE.

JESSE A. MORRISON, OF MOUNTAINAIR, NEW MEXICO.

COMBINATION-RIG FOR DRILLING.

1,327,403.

Specification of Letters Patent.

Patented Jan. 6, 1920.

Application filed December 11, 1918. Serial No. 266,256.

To all whom it may concern:

Be it known that I, JESSE A. MORRISON, a citizen of the United States, residing at Mountainair, in the county of Torrance and State of New Mexico, have invented certain new and useful Improvements in Combination-Rigs for Drilling, of which the following is a specification, reference being had to the accompanying drawings.

10 This invention relates to combination rigs for well drilling or the like, and it is an object of the invention to provide a novel and improved device of this general character whereby the rig may be changed from standard to rotary or vice versa with a minimum of labor and time.

It is also an object of the invention to provide a novel and improved combination rig of this type wherein the rotary or standard are so related as to offer no obstruction one to the other during its operation.

A further object of the invention is to provide a novel and improved combination rig of this type which does not interfere 25 with spudding or pipe driving or any standard work, and wherein the calf wheel can be used with convenience for handling underreamer and other work. An additional object of the invention is to provide a novel 30 and improved combination rig of this general character wherein the band wheel shaft is operatively connected with the drive shaft of the rotary mechanism so that either the standard or the rotary may be operated by the same motor and which motor may be of any type preferred.

The invention consists in the details of construction and in the combination and arrangement of the several parts of my improved rig whereby certain important advantages are attained and the device rendered simpler, less expensive and otherwise more convenient and advantageous for use, as will be hereinafter more fully set 45 forth.

The novel features of my invention will hereinafter be definitely claimed.

In order that my invention may be the better understood, I will now proceed to describe the same with reference to the accompanying drawings, wherein:

Figure 1. is a fragmentary view in side elevation illustrating a combination rig

constructed in accordance with an embodiment of my invention; and

Fig. 2 is a view in top plan of the structure as shown in Fig. 1.

As disclosed in the accompanying drawings, 1 denotes a band wheel shaft rotatably supported in a conventional manner and 60 which is provided at one extremity with a crank 2 with which is adapted to be operatively connected a pitman 3 coacting with an end portion of the walking beam 4. Also affixed to the band wheel shaft 1 is a band 65 wheel 4 and the tug pulley 5 as employed in the conventional type of standard rigs. The shaft 1, adjacent its opposite extremity has also affixed thereto the iron tug wheel 6 for the calf wheel 7 rotatably supported in 70 a conventional manner by the calf wheel posts 8.

9 denotes the floor of the derrick D and said floor 9 is provided with a rotary table 10 for properly turning the rotary drill 75 tools and said table is provided at its upper face with an annular gear or rack 11 with which meshes a gear 12 carried by a suitably supported shaft 14. The shaft 14 has also affixed thereto a sprocket 15 around 80 which passes a chain 16 also directed around a drill drive sprocket coacting with the drive shaft 17 of the rotary drilling outfit R, said shaft extending longitudinally of the rigging.

The outfit R is arranged at one side of the derrick floor 9, mounted upon a derrick mud sill 18 and at a point between the calf wheel 7 and the bull wheel 19.

Bolted as at 20 to the jack post 21 and 90 bolted as at 22 to the sub-sill 23 is an up-standing post 24 and extending upward from certain of the floor sills 23' and the mud sill 18 are the posts 24^a in longitudinal alinement with the post 24. Supported by 95 the posts 24 and 24^a is a line shaft 25 and the end portion thereof adjacent the post 24 is provided with a gear 26 in mesh with a gear 27 mounted upon the band wheel shaft 1. The line shaft 25 is substantially in parallelism with the drive shaft 17 of the rotary drilling outfit hereinbefore referred to. Loosely mounted on the opposite end portion of the shaft 25 is a sprocket wheel 28 around which is directed a chain 29 which is 100 also disposed around a sprocket 30 carried

2
by the drive shaft 17 of the outfit R. The sprocket 28 is provided with a clutch face 31 with which engages a clutch member 32 mounted for sliding movement upon the shaft 25 but capable of movement endwise thereof so that the sprocket 28 may be rendered operative or inoperative in accordance with the requirements of practice.

When it is desired to employ the standard 10 rig the clutch member 32 is disengaged from the clutch face 31 of the gear 28 and when it is desired to employ the rotary outfit R said clutch member 31 is engaged with the face 32 of the gear 28 and the pitman 3 15 connected from the crank 2. It will also be noted that the position of the rotary outfit R and its coacting parts relative to the remaining elements of the rig are such as to readily permit spudding or pipe driving or 20 any standard work and that the calf wheel 7 can be used for handling underreamers or the like without hindrance.

From the foregoing description, it is thought to be obvious that a rig constructed 25 in accordance with my invention is particularly well adapted for use by reason of the convenience and facility with which it may be assembled and operated, and it will also be obvious that my invention is susceptible

of some change and modification without departing from the principles and spirit thereof, and for this reason I do not wish to be understood as limiting myself to the precise arrangement and formation of the several parts herein shown in carrying out my invention in practice except as herein-after claimed.

What is claimed is:

A drill rigging of the class described comprising a band wheel shaft adapted to operate a walking beam, a rotary carriage, an outfit coacting with the carriage and positioned at one side of the rigging, said outfit including a drive shaft extending longitudinally of the rigging, a line shaft driven by 45 the band wheel shaft, said line shaft also extending longitudinally of the rigging, an operative connection between the line shaft and the drive shaft of the outfit, and means for rendering said last named connection inoperative.

In testimony whereof I hereunto affix my signature in the presence of two witnesses.

JESS A. MORRISON.

Witnesses:

BOB ADAMS,
H. J. ANDREWS.
